UNITED STATES PATENT OFFICE.

ALFRED WARNE, OF MIAMI, FLORIDA.

COLLAPSIBLE BARREL.

1,116,770.

Specification of Letters Patent. Patented Nov. 10, 1914.

Application filed March 6, 1913. Serial No. 752,514.

To all whom it may concern:

Be it known that I, ALFRED WARNE, citizen of the United States, residing at Miami, in the county of Dade and State of Florida,

5 have invented certain new and useful Improvements in Collapsible Barrels, of which the following is a specification.

This invention relates to an improvement in collapsible barrels.

10 The primary object of the invention is to provide a barrel which when not in use may be folded to occupy a comparatively small space and which when extended for use will be sufficiently rigid to withstand the handling to which devices of this character are subjected.

A further object of the invention is to provide a folding barrel which may be formed of the material of which produce 20 barrels are usually constructed, the construction being such that should the folding sections become damaged, they may be easily replaced or repaired.

A still further object of the invention is 25 to provide a structure which may be quickly assembled and disassembled, thereby allowing the receptacles to be dumped as they are taken from a vehicle, disassembled and replaced, or their contents removed by disassembling the staves.

A still further object is to provide a construction in which the sections are connected by means other than complicated metallic fasteners which are not only expensive 35 to manufacture but which add to the weight of the barrel and hinder the proper handling of the same, as well as require considerable time in the assembling and disassembling of the sections.

40 In the drawings: Figure 1 is a perspective view showing the sections assembled; Fig. 2 is a transverse section; Fig. 3 is a detail view showing the manner in which the hingedly connected staves are secured to 45 the head of the barrel; Fig. 4 is a detail view of a modified form of fastening means; and Fig. 5 is a detail view showing in end elevation the sections of the barrel in folded relation.

50 In the drawings, 10 designates the head of the barrel which is preferably hexagonal. Each of the straight edges 11 is provided with a loop or staple 12, said staples being of a length in excess of the thickness of the 55 members which constitute the staves of the barrel. The edges 14 of the stave members

15 are hingedly connected, there being a number of hinges 16 connecting each pair of staves consistent with the length of the 60 staves.

It has been found in practice that in constructing a barrel of standard or ordinary size, the adjacent edges of the various staves may be connected by one pair of hinges, it being necessary to employ more than two 65 hinges in connecting the several staves only when the barrel is made of unusual size. In the preferred embodiment, the body of the barrel consists of eight staves which are so connected that they may be folded 70 one upon the other when the barrel is disassembled and collapsed for shipping or packing. In order to permit the barrel staves to be folded in this manner, the pairs of hinges of the various adjoining edges of 75 the staves have been alternately disposed exteriorly and interiorly of the staves, the terms "exteriorly" and "interiorly" being applied with reference to the assembled position of the staves, as illustrated in Fig. 1. 80 In securing the hinges to the staves, screws, rivets or any other suitable fastening devices of similar nature may be employed.

In assembling the staves and head, one of the staples 12 is inserted within an opening 85 17 formed in one end of one of the end staves. The remaining staves are then placed about the head and the staples 12 of each of the straight edges 11 of the head inserted within the openings 17 of the adjacent staves. When the staves are thus 90 completely assembled about the head, and all of the staples project through the same, a cable 18 is passed through the staples and its terminals connected, securely locking 95 the staves in position and supporting the head against displacement. This cable is preferably formed of wire in order that its ends may be twisted to form a rigid connection, but any suitable form of connecting 100 member may be used.

The staves adjacent their terminals remote from the head are preferably held together by means of a wire 19 which passes through staples 20 carried by the staves, the 105 terminals 21 of the wire being twisted when the staves are assembled. It will be noted by this construction that the staves are effectively supported adjacent both of their terminals. When the staves are thus assembled with respect to the head, a second head may be inserted within the open end 110

of the barrel or the barrel may be used with one open end. While the head 10 is illustrated as hexagonal and the staves shown as eight in number, it will be noted that the 5 heads may be formed with any number of straight edges and the staves of a number consistent with the number of straight edges. It will also be noted that while the head 10 is shown as constructed of a single 10 piece of material, it may be made in sections hingedly connected in order that the barrel when collapsed may occupy a comparatively small space.

In Fig. 4, a modified form of head securing mechanism is illustrated. In this 15 form, the staples 12 receive pegs 22, the pegs being tapered in order that they may be driven into the staples and securely wedged against displacement. By this construction, 20 it will be seen that the cable 18 may be dispensed with and the staves effectually secured to the head.

Having thus described my invention, what I claim as new and desire to secure by 25 Letters Patent is:—

1. A collapsible barrel including a head formed with a plurality of straight edges, staves hingedly connected, means supported by each of the straight edges and disposed 30 to extend through the staves, and a flexible member disposed to connect said means to hold the staves in contact with the head.

2. A collapsible barrel comprising a head formed with a plurality of straight edges, a 35 loop carried by each of said edges, hingedly

connected staves provided with openings disposed to receive said loops, and a flexible member disposed to extend through the loops to hold said staves in contact with the head.

3. A collapsible barrel including a head, loops carried by the head, a plurality of hingedly connected staves, said staves being formed with openings disposed to receive said loops, and means extending through 45 the loops and embracing the staves to hold the staves in contact with the head.

4. A collapsible barrel including a head, a plurality of staves, hinges connecting the staves, and a flexible member embracing the 50 staves and connected to the head for holding the staves in contact with the head.

5. A collapsible barrel including a head member, loops extending laterally from the periphery of the head member, a plurality 55 of hingedly connected staves provided adjacent their lower terminals with transversely extending slots adapted to receive the said loop members, and a flexible member insertible through the projecting terminals of the loops for holding the staves in contact with the periphery of the head member.

In testimony whereof I affix my signature in presence of two witnesses.

ALFRED WARNE. [L. S.]
